ADJUSTABLE LEVEL CASE

Max Wyler, Winterthur, Switzerland

Application May 17, 1947, Serial No. 748,769
In Switzerland March 18, 1946Section 1, Public Law 690, August 8, 1946
Patent expires March 18, 1966

4 Claims. (Cl. 33—214)

1

The known cases for level tubes are mounted in rotary position on an axis at one end and adjustable in the vertical axial plane at the other end by means of an adjusting screw perpendicular to the first axis. However, this type of correcting device cannot give full satisfaction in the case of precision levels.

The present invention relates to an adjustable case for level tubes which in every way meets the requirements made of it for high-precision measuring purposes.

This is made possible by the invention in that the tubular container is mounted at its one end to rotate in all directions round a certain point, whereas the other end has an axially sprung bracket. This latter rests laterally on adjusting screws.

In the drawing three different constructional embodiments are exemplified, as follows:

Fig. 1 an axial section of a first,

Fig. 2 of a second, and

Fig. 3 of a third constructional embodiment of the level case.

The level 1 is provided with an infusion mass 2 which is poured in a tubular container 3 and blocked. The water level casing 4 is provided with a longitudinal bore-hole 5 to hold the tubular container 3 with the level. The window 6 of the metal case, the window 7 of the tubular container and the window 8 of the outer case fit in with each other and permit of observing the air-bubble 9 of the level. One end of the tubular container 3 rests, as shown in Fig. 1, by means of a ball-seating 10 against a ball-bearing 11, which latter is in turn mounted in a ball-seating 12 of the bore-hole 5. In the other end of the tubular container 3 a piston 13 is mounted in longitudinally adjustable position, with a conical head 14 at its end projecting from the tubular container. Between the end of the tube and the offset 15 of the conical head an elastic ring 16 is inserted which resiliently supports the cone. Three adjusting screws 17 are screwed into the water-level casing 4 radially to the cone axis in such a way that their tips touch the cone 14. The elastic ring 16 presses on the one hand the tubular container 3 against the ball bearing 11 and on the other hand the cone 14 against the tips of the adjusting screws 17. In this way the tubular container is mounted at both ends without any play whatsoever and in totally immovable position. The level can be corrected, both in the inclination of the level to the horizontal and on both sides, by screwing the individual adjusting screws 17 backwards and forwards.

2

In the case of the constructional embodiment shown in Fig. 2 the one end of the tubular container 3 is supported by means of a spherical cap 18 screwed on, against the hollow cone 12 of the bore-hole 5 of the water-level casing 4. For the sprung support of the cone 14 at the other end of the tubular container 3 a compression spring 19 is used, which rests on the one hand against the cone and on the other hand against a base-plate 20 inserted in the tubular container 3.

Fig. 3 shows a constructional embodiment in which the one end of the tubular container 3 bears a needle 22 provided with a spherical tip 21 and rests with this against a cone-seating 23 of the water-level casing 4. At the other end of the tubular container 3 a jacket 24 provided with a conical tip 14 is mounted in longitudinally adjustable position. To support the cone jacket 14, 24 a compression spring 19 is again used, resting on the one hand against the cone and on the other hand against a base-plate 20 inserted in the tubular container 3.

While the form of embodiment of the invention as herein disclosed, constitutes a preferred form, it is to be understood that some changes may be made in the arrangement, construction and combination of the various parts of my invention, and it is my intention to cover by my claims such changes as may reasonably be included within the scope thereof.

I claim as my invention:

1. In a level, in combination, a body and a bubble tube carrier both formed with a bubble tube opening, a bubble tube, spherical seating means and conical counter-seating means arranged between said carrier and said body at one end of, and substantially coaxially with, said carrier, a conical member resiliently mounted at the opposite end of, and substantially coaxially with, said carrier, and three setting screws adjustably and symmetrically seated in said body for engagement of their forward ends with said conical member.

2. In a level, in combination, a body and a bubble tube carrier both formed with a bubble tube opening, a bubble tube, a ball seated between a conical seat within said body and a conical seat at one end of, and substantially coaxially with, said carrier, a conical member resiliently mounted at the opposite end of, and substantially coaxially with, said carrier, and three setting screws adjustably and symmetrically seated in said body for engagement of their forward ends with said conical member.

3. In a level, in combination, a body and a

bubble tube carrier both formed with a bubble tube opening, a bubble tube, a globular end portion provided substantially coaxially with, and at one end of, said tube carrier, conical seating means at said body for reception of said globular portion, a conical member resiliently mounted at the opposite end of, and substantially coaxially with, said carrier, and three setting screws adjustably and symmetrically seated in said body for engagement of their forward ends with said conical member.

4. In a level, in combination, a body and a bubble tube carrier both formed with a bubble tube opening, a bubble tube, spherical seating means and conical counter-seating means arranged between said carrier and said body at one end of, and substantially coaxially with, said carrier, a conical member, formed with a cylindrical portion which is slidably mounted by means of a cylindrical portion at the end of said carrier, resilient means between said conical member and said carrier, and three setting screws adjustably

and symmetrically seated in said body for engagement of their forward ends with said conical member.

MAX WYLER.
